LANDING GEAR WARNING SWITCH CUTOUT

Albion L. Ostlund and John A. Minshull, Seattle,
Wash., assignors to Boeing Aircraft Company,
Seattle, Wash., a corporation of Washington

Application November 29, 1941, Serial No. 420,996

4 Claims. (CL 177—311)

It is customary practice, in airplanes which have retractable landing gears, to provide a signal, usually a horn located closely adjacent the pilot's ear, in a circuit which includes a switch that is closed when the landing gear is retracted, and to arrange to energize that signal by a normally open push button in the signal circuit, located in the path of the throttle lever, in such manner that as the throttle lever approaches or nearly reaches closed position the horn is sounded. Since the closing of the throttle is normal in gliding to a landing, the arrangement described serves to warn the pilot, should he prepare to land while his landing gear is still retracted.

While such a warning signal has proven its value in numerous instances, there are other occasions when the pilot, in flight, may wish to close his throttle and glide or dive, while his landing gear is still retracted. Such maneuvers are particularly appropriate to fighter airplanes engaged in individual combat, and it is distracting to have a signal horn sounding at such times. However, while it is a simple matter to provide a cut-out switch in the signal circuit, if there is such a switch it may happen that the pilot will turn off the signal and forget to close the switch again, and then he may attempt to land with his landing gear up, and will receive no warning signal as he starts his glide. It follows that it is dangerous to provide such a cut-out switch, or a similar cut-out arrangement, and so heretofore the pilot has been faced with the dilemma of enduring the horn whenever in flight he closes his throttle, or of risking the possibility of a landing with his landing gear up, or it has been necessary to provide a mechanically and electrically complicated shut-off system, with the always-present possibility of failure, and of consequent disaster.

It is the object of the present invention to provide a device for incorporation in and in connection with such a warning signal system, whereby the pilot at will can deenergize the warning signal, but which will automatically operate by advance of the throttle toward open position to place the signal in condition for operation again, whenever the throttle is next moved toward or substantially to closed position. By such an arrangement the pilot can always at will deenergize the signal, after it commences to sound, yet is assured that the signal will always be ready to sound again whenever it is proper that it should.

Again, a further object is to provide such a

warning signal cut out, which is of simple construction, and simple to install, and which is located conveniently to the pilot as he operates the throttle lever.

With these and other objects in mind, as will appear hereafter, our invention comprises the novel arrangement, and the novel parts thereof, as shown in the accompanying drawing in a preferred form, and as will be hereinafter more fully explained and defined by the claims which close this specification.

In the accompanying drawing the invention has been shown diagrammatically and also in a form which is at present preferred by us.

Figure 1 is a side elevation of the throttle lever, and of the associated cut-out.

Figure 2 is an enlarged view of the same, taken at right angles to Figure 1.

Figure 3 is a detail, partly in section and partly in elevation, illustrating the cut-out and its relation to the throttle lever.

Figure 4 is a diagrammatic illustration of the principles of the invention.

Referring first to Figure 4, the throttle lever 1 is rotatably mounted to move about the axis 10, and the landing gear, generally indicated by the numeral 4, is mounted for retraction to swing about the axis 40. The warning signal 3 may be considered as an electric diaphragm horn, and in its circuit is included an energy source 30, a self-closing switch 34, which is opened only as the landing gear reaches its projected or landing position, and a normally open switch 31, the movable push button 33 of which is disposed in the path of the throttle lever or of some member which moves with the latter. The signal circuit may also include a switch 32, which is normally closed but which can be used to deenergize the entire circuit at will. This switch 32 preferably is located in a relatively inaccessible spot, where it is not likely to be opened by the pilot while in flight, except in case of emergency.

The movement of the throttle lever 1 between open and closed positions is under the control of the pilot, and the limits of its movement are determined by suitable stops, not shown. It is so arranged with relation to the movable member 33 of the actuating switch 31 that the button 33 is not depressed by the throttle lever, even when the latter reaches its full closed position, which full closed position is represented at C in Figure 1. However, a spacer member 2 is interposed between the throttle lever and the button 33, or between an adjustable spur 11 car-

ried upon the throttle lever and the button 33. This spacer member is of such size that it is contacted by the spur 11 when the throttle lever reaches the point B, just prior to its reaching its closed position C. When the spacer member 2 is thus contacted and moved by the throttle lever it transmits this movement to the button 33, and thereby the signal 3 is energized if the landing gear 4 is still retracted. To permit such movement of the spacer member 2 it may conveniently be formed as an arm or finger pivotally mounted upon a pivot post 20, supported in a fixed bracket 21 which also supports the switch 31. Whether it is mounted upon the bracket or upon the throttle arm is largely immaterial.

In order to enable the spacer member 2 to be held normally in its operative position, interposed between the throttle lever and the switch, yet to be moved at will from such operative position, it is movable bodily axially along the post 20 by pressing upon the handle 22, in opposition to the spring 23.

As will now be evident, the spacer member 2 is held by the spring 23, normally in interposed position, where it will transmit movement of the throttle lever, as the latter nears closed position, to the switch to energize the signal. However, if the pilot wishes to deenergize the signal he has only to press upon the handle 22, and thereby the spacer member 2, even though swung aside as shown in dot-dash lines in Figure 2, may be depressed below the spur 11. When so depressed it may not move back into interposed position, being held by the spur, but immediately the throttle lever and its spur 11 are moved towards open position the spring 23 moves the spacer member 2 back into its normal interposed position. The end of the button 33 is shaped to guide the deflected finger 2 back to its normal position. Now, if the throttle lever is again moved toward closed position, automatically, and without thought on the part of the pilot, the signal is again energized. If the pilot desires to deenergize it, this must be done positively, and after each return of the throttle toward closed position. Always after movement of the throttle away from closed position the signal circuit is again placed in condition for energization, without any thought or conscious action on the part of the pilot.

The entire device is simple, light, and requires no wiring connections. It is always in position for use, conveniently to the pilot as he operates the throttle lever, and it is always ready for operation.

What we claim as our invention is:

1. In combination with the throttle lever of an airplane, movable in a fixed path between open and closed positions, and with the retractable landing gear, a signal, means to energize said signal if the throttle lever is moved substantially to closed position while the landing gear is retracted, said means including an actuator disposed in the path of the throttle lever, but spaced sufficiently from the latter, in its closed position, that the actuator can not be operatively engaged for energization of the signal, a spacer member normally interposed between the actuator and the throttle lever, of a size to span the gap therebetween, for energization of the signal as the throttle lever substantially reaches closed position, a support for said spacer member permitting its movement at will

from between the throttle lever and the actuator, to deenergize the signal at will, and means active upon reverse movement of the throttle lever to restore the spacer member immediately to its normal interposed position.

2. In combination with the throttle lever of an airplane, movable in a fixed path between open and closed positions, and with the retractable landing gear, a signal, means to energize said signal when the throttle lever is moved substantially to closed position while the landing gear is retracted, said signal-energizing means including a fixedly positioned actuator having a movable element disposed in the path of the throttle lever, but sufficiently spaced from the closed position thereof that its movable element can not be moved for signal energization, a spacer member fixedly positioned relative to the actuator, of a size and so disposed as to transmit final closing movement of the throttle lever to the actuator's movable element, for signal energization, a support for the spacer member arranged to afford such movement of the spacer member with the throttle lever and actuator, and to afford also manual movement of the spacer member relative to the actuator and from its interposed position, thereby to deenergize the signal at will, means to interdict return of the spacer member to its interposed position following its signal-energizing movement and prior to reverse movement of the throttle lever, and resilient means active upon the spacer member to return it to its interposed position immediately following movement of the throttle lever towards open position.

3. In combination with the throttle lever of an airplane, movable in a fixed path between open and closed positions, and with the retractable landing gear, a signal, means to energize said signal if the throttle lever is moved substantially to closed position while the landing gear is retracted, said signal-energizing means including a spur projecting from the throttle lever in the plane of its movement, a fixedly positioned actuator having a movable element disposed in the path of the spur, but spaced sufficiently therefrom, in closed position, that the spur can not move such element for energization of the signal, a spacer member normally interposed between the spur and the movable element of the actuator, of a size to transmit movement of the throttle lever to the movable actuator element, for energization of the signal as the throttle lever approaches closed position, a support for the spacer member arranged to afford movement of the spacer by and with the spur, and also manually transversely of the spur into inoperative position wherein it is held by the spur, and spring means active upon withdrawal of the spur and throttle lever towards open position, to restore the spacer member immediately to its normal interposed position.

4. The combination of claim 2, wherein the spacer member comprises a finger and a pivot support therefor the axis whereof is generally parallel to but offset from the throttle lever's path, said spacer member being mounted upon said pivot support for swinging movement upon engagement of its outer end by the throttle lever, and for bodily axial movement into and from its inoperative position.
